UNITED STATES PATENT OFFICE

CARL EDWIN CARLSON, OF LONG ISLAND, NEW YORK

REMINDER

Application filed September 9, 1930. Serial No. 480,632.

This invention relates to indicators and has particular reference to reminders.

One object of the invention is to provide a device of the character described having improved means of a simplified nature for mounting an indicator and permitting adjustment thereof to present any desired indicia.

Another object of the invention is the provision of an indicator or reminder having one or more indicia bearing elements of novel and improved construction and arrangement, affording a simple, neat, and compact device.

Another object of the invention is to construct a device having one or more indicator elements mounted on a flexible or elastic means or having coacting resilient means so that while all the elements have a unitary mounting, they are resiliently held in required position and may be moved and set to present a desired indicia, on deforming the resilient means, the element so operated being thereafter again resiliently retained in position.

Another object of the invention is the provision of a reminder which can be disposed against any suitable surface, such as a bar, or the spoke of an automobile handwheel with coordinated improved holding and attachment means, whereby the device may assume the general form of a loop, or the like.

Another object of the invention is to furnish a device of the type mentioned having few and simple parts, and which is inexpensive to manufacture, easy and convenient to operate, and reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference character throughout the several views.

In the drawings:

Figure 1 is a top plan view of a steering

wheel showing an embodiment of my invention applied thereto.

Fig. 2 is an enlarged sectional view taken on line 2—2 of Fig. 1.

Fig. 3 is a plan view of the device in open 55 dismounted position.

Fig. 4 is an end view of an attachment block.

Fig. 5 is an enlarged sectional view taken on line 5—5 of Fig. 3. 60

Fig. 6 is a view of a modified attachment means.

The advantages of the invention as here outlined are best realized when all of its features and instrumentalities are combined 65 in one and the same structure, but, useful devices may be produced embodying less than the whole.

It will be obvious to those skilled in the art to which the invention appertains, that 70 the same may be incorporated in several different constructions. The accompanying drawings, therefore, are submitted merely as showing the preferred exemplification of the invention.

Generally described, the invention provides an indicator which may be broadly contemplated as applicable for a great variety of uses, and in connection with different types of machines, to act as a signal, reminder, or recorder, according to the circumstances, and regardless whether the device be automatically or manually operated. To illustrate the principle involved, it is sufficient to show a simple embodiment of the invention adapted 80 for use on automobiles, to be displayed in some convenient and conspicuous position, and upon being set, to act as a reminder of the needs or requirements of the automobile, or of certain acts to be performed in connection therewith. The device includes a plurality of indicia bearing elements, each of which may have a legend on one side thereof, or the same legend formed in different colors on opposite sides thereof. Thus if the legend 95 "Oil" in red is presented, the driver is thereby reminded that the automobile requires oil. After oil has been supplied to the car, the element bearing the oil indicia is moved to conceal "Oil" in red, thus causing "Oil" in some 100

other color to appear for the purpose merely of identifying the element. Any number of these elements may be provided, each bearing a different indicia. Coacting with the elements is a mounting so constructed as to permit a pivotal adjusting movement of the elements. Said means may also have an elastic coaction with the elements to retain them in set position. It will be appreciated that the reminder device may be attached in flat position as shown in Fig. 3, to a support and function as specified, or it may be disposed around a suitable bar, tube, or other available projection. In connection with steering wheels, the device may be mounted on a spoke of the wheel at a predetermined point thereon, though preferably in angularly adjustable relation, and also, if desired in longitudinally sliding relation thereto. A single indicator element may also be used having different indicia thereon, spaced a small angle apart, as, for example, a hexagonal prism pivoted about its longitudinal axis. With the above general characteristics in mind, the device specifically includes a plurality of narrow elongated indicator elements, having openings therethrough intermediate or centrally of the ends thereof, through which a pivot member is passed. While the openings of the elements may be in the form of slots to aid in the pivotal action, it is preferred to afford a resilient coaction, as, for instance, by making the pivot member elastic. For that purpose the latter may consist of a spring or of an elastic band. Being flexible, the device may be applied around a spoke of any shape in cross section, and engaged thereon by suitable attachment means.

Referring in detail to the drawings 10 denotes a device embodying the invention. The same may be applied to any suitable machine or article, as, for example the spoke 11 of an automobile steering handwheel 12 to act as a reminder for the needs of the car.

The device 10 includes a plurality of indicator elements 13 made of any suitable material, such as bakelite, glass, metal or wood, all of these elements being preferably of uniform size and shape, and functioning as indicators by reason of indicia 14 placed or impressed thereon. While the elements may be of any suitable shape and construction, they may merely consist of solid rod stock of uniform length and adapted to be evenly disposed side by side.

Formed intermediate the ends of the elements 13, preferably at the centers thereof, are diametral passages 15 through which a suitable pivotal and holding member 16 may extend. This member 16 may be flexible and is preferably elastic or may have elastic means coacting therewith or with the elements. A simple construction may consist in forming member 16 of an elastic band, having rubber therein, or of a coil spring.

shown in Fig. 6. At the ends of the member 16 are any suitable attachment or fastening means 18 for individual engagement with a support so as to hold the elements 13 against the support. Preferably, the attachment means are constructed to interconnect the ends of the member 16 to form the device 10 into a loop. Since member 16 is flexible, the loop will conform to any shape of support or wheel spoke. Each element 13 may include the same legend in different colors on opposite sides thereof, legend in red being normally concealed against the steering wheel spoke while the other legend in some other color being exposed to identify the element bearing the particular legend. Thus if the engine jacket requires water, the operator grasps the element bearing the legend "Water," stretching the member 16 and pivotally swings the element to bring the reverse side upward to show the legend "Water" in red. Upon releasing the element, the elastic member 16 draws the element snugly against the spoke holding it in set position. When the water has been supplied to the engine, the same operation is repeated, to bring the element back to initial position. Other legends that may be used on the other elements include, for example, "Gas", "Battery", "Tires", "License", "Insurance", etc.

The device 10 may be angularly adjusted around the spoke to bring the required legend uppermost, and it may also be adjusted longitudinally of the spoke to any convenient position.

Coacting with the fastening means is a block 19 which may constitute a part thereof or an enclosure therefor, this block having an opening 20 for that purpose, and a passage 21 communicating therewith through which the member 16 is passed. The fastening means 18 may include, if desired a hook 22 and an eye 23, and the hook may be of sufficient length to enter the opening 20 and engage the eye. The block 19 may carry suitable advertising on one or both faces thereof.

In Fig. 6 is shown a modification, wherein a block 24 has a central opening 25 to receive the fastening means 18. Alined passages 26, 27 are provided communicating with the opening 25, the latter passage being of sufficient size to admit the hook 22, and the attachment of the hook and eye occurring by manipulation through opening 25.

The device shown in the drawings constitutes but one possible embodiment of the invention. If the spoke whereon the device 10 is mounted is tapered, the provision of a flexible member 16 will permit the device to be moved to the small end of the spoke and an indicator element pivotally set as above stated, and the device returned to the large end of the spoke. The scope of the invention is indicated in the following claims.

I claim:

1. A device including a plurality of narrow elongated elements disposed side by side, each element having indicia on opposite faces thereof, each element having a transverse passage therethrough at a point adjacent to the center between the ends of the element, a flexible elastic member threaded through said passages, and attachment means for uniting the ends of the elastic member whereby the elements may be disposed flat against a surface and individually pivotally moved about said elastic member to present either indicium, on stretching the elastic member.

2. A device including in combination with a support, a plurality of narrow elongated elements disposed side by side around the support, said elements having each a passage intermediate the ends thereof, a flexible member passing through said passages and having the ends thereof interconnected to hold the elements around the support, each element having indicia on opposite sides thereof, said member being elastic so that it may be stretched to pivotally move any of said elements about the member to present either indicium.

3. The combination with a bar, of means including a loop member, the latter taking around the bar, and a plurality of indicator elements separately movably attached to the loop member, said means having an elastic coaction with the elements, whereby an element is resiliently held against the bar and can be moved about the loop member to present any desired indicia.

4. A device including a plurality of indicator elements, a flexible member interconnecting the elements, and releasable attachment means for the ends of the member, said attachment means including fasteners secured to the ends of the member, and a block having an opening for receiving said fasteners therein.

5. A device including a plurality of narrow elongated elements disposed side by side, each element having indicia on opposite faces thereof, each element having a transverse passage therethrough at a point adjacent to the center between the ends of the element, a flexible elastic member threaded through said passages, and attachment means for the ends of the elastic member, whereby the elements may be disposed flat against a surface and individually pivotally moved about said elastic member to present either indicium, on stretching the elastic member, the attachment means including an eye and hook for opposite ends of the elastic member, and a block having an opening to receive the eye and hook therein, the block having a hole for receiving the elastic member, the hook being movable out of the block opening, said block being adapted to carry advertising indicia.

6. A device including a relatively station-

ary support, a plurality of narrow elongated indicator elements disposed in side by side relation along said support, and an elastic tension member connected to said indicator elements intermediate the ends of each and extending transversely to said elements, said elastic member coacting with said indicator elements for swinging movement of the same about the elastic member to disclose a desired indicium, the elastic member holding the indicator elements against the support to prevent the swinging movement, whereby an indicator element may be swung by elongating the elastic member.

7. In combination with a support, a plurality of indicator elements disposed upon the bar, and elastic tension means holding the indicator elements against the bar, the indicator elements being rotatable about the elastic means to present a desired indicium, and the indicator elements coacting with the support to prevent rotation of the same and being released for rotation on stretching the elastic means.

8. A device including a bar, a plurality of indicator elements disposed therearound, and means extending around the bar for holding said elements thereon, said means having a resilient coaction with respect to the bar for movement of an individual indicator element relative to the bar, said indicator elements and means being angularly movable around the bar to present any desired indicator element.

9. A device including a wheel having a tapered spoke, an elastic loop means extending around said spoke, indicator elements separately connected to said loop means in side by side relation and held by the latter against the spoke, whereby the indicator elements and loop means are adjustably movable along said spoke with the loop means deforming to accommodate the spoke.

In testimony whereof I affix my signature.

CARL EDWIN CARLSON.
